VIBRATION ISOLATOR DEVICE

John W. Patton, Philadelphia, Pa., assignor to
American Car and Foundry Company, New
York, N. Y., a corporation of New Jersey

Application November 19, 1948, Serial No. 60,909

4 Claims. (Cl. 248—358)

1

This invention relates to furniture and more particularly to furniture mounting means incorporating vibration isolator or absorbing devices.

Vibration and shock developed in railroad cars and other vehicles are transmitted through the underframing and body to the supporting means for furniture in the car rooms. When furniture, such as tables, are supported on the car wall as well as on legs, the vibration and shock are transmitted from the car wall and the floor. The effect of vibration and shock transmitted to tables and other furniture is objectionable to vehicle passengers.

An object of the invention is to reduce vibration and shock transmitted to vehicle furniture through the provision of isolator devices in the supporting means.

Another object of the invention is to provide a novel isolator device of the compression type.

A further object of the invention is to reduce the vibration and shock flowing to a table of the wall attachment type through the use of isolator devices in the supports.

These and other objects of the invention will be apparent to those skilled in the art from a study of the following description and accompanying drawings, in which:

Figure 1 is a perspective view of a fragment of a vehicle room having a table set up therein.

Figure 2 is a vertical elevational view in the room showing a portion of the table and one of the wall supports for the table.

Figure 3 is a sectional view taken on line 3—3 of Figure 2.

Figure 4 is a view similar to Figure 1 showing hinged supporting means for the table.

Figure 5 is a vertical elevational view in the room showing a portion of the table and with one of the hinged supporting means partly in section taken on line 5—5 of Figure 6.

Figure 6 is a view taken on line 6—6 of Figure 5.

Figure 7 is an end view of the lower portion of the table leg and associated vibration isolator device.

Figure 8 is a side view of the lower portion of the table leg with an applied isolator device shown in section.

The invention is shown applied to a table 10 located in a vehicle room, which may be the interior of a railroad car, of which an outer wall 11 and a floor 12 are illustrated. The table is preferably of the detachable wall type used in railroad cars and is formed of sheet wood or other suitable material.

2

The table is preferably provided with a three point support consisting of leg 13 adjacent one end and a pair of spaced supporting means 14 at the other end. Wall 11 has a continuous anchor strip 15 extending longitudinally thereof having a slot formed by an under turned flange 16 providing an anchor for hanger brackets 17 forming a part of the supporting means. These brackets have an out turned upper flange 18 adapted to be inserted into the slot and over the underlying anchor flange of strip 16 and that also have an out turned base portion 19 for carrying the table. Between the hanger bracket bases 19 and the wall end portion of the table, I arrange vibration and shock isolator devices 20.

In the arrangement shown in Figures 4 to 6 inclusive, there is a backing strip 21 between the anchor strip and wall 11 and such backing strip projects beneath the anchor strip and serves as a protector plate for the wall. This form of the invention differs from that shown in Figures 1 to 3 inclusive in that the supporting bracket or hanger means is formed of two hinged sections instead of being rigid. The upper section 22 of this hinged hanger supporting means has the out turned flange 18 adapted to be inserted over the flange 16 of the anchor strip and is connected with a lower section 23 by hinge 24. The lower section 23 has an outwardly extending table supporting base flange 19 as previously described. In this form of the invention, the isolator device 20 is arranged between the base flange 19 and the wall end portion of the table. Member 22 has oppositely disposed bumper devices 25 and 26 secured thereto, the device 26 being located to engage against the depending portion of the backing strip and the bumper device 25 serving to be engaged by the table top when it is swung upwardly.

The isolator devices of the wall supported hanger brackets shown in both forms of the invention are similar so that a description of one device will suffice. A facing strip 27 applied to the top of the base supporting flange 19 provides a seat for the cup-shaped base 28 of the isolator device. A bowl-shaped rubber member 29 formed with a cylindrical base portion is mounted in the base 28 to which it is vulcanized or bonded and the upper edge portions of member 29 are bonded to the base of an angular strip 30 adapted to be attached to the wall end portion of the table by screws 31. Base flange 19, facing strip 27, base 28 and the circular base portion of the rubber member 29 are formed with aligned

openings for the reception of bolt 32 and an internally threaded metal sleeve 33 is vulcanized in the opening of member 29 for engagement by bolt 32. The isolator device is clamped on the supporting bracket or hanger flange 19 by the engagement of bolt 32 with sleeve 33 and the angular strip of the device is attached to the table by screws 31. The isolator device is formed of a unitary structure that is readily applied to or detached from the table and the hanger support. These isolators serve to absorb wall vibrations and shocks before they reach the table.

The leg 13 may have a hinged attachment with the table, of a conventional nature, and the foot of the leg is provided with a vibration and shock isolator device 40. This device is generally similar to that utilized between the wall hanger brackets and the table. A bowl-shaped rubber member 41 has its upper edge portion bonded to a metal plate 42 that is adapted to be detachably secured to the bottom of the table leg by screws 43. The reduced diameter base portion of the rubber member 41 is cylindrical and is bonded to the inside of a flanged metal annular base member 44. The base member and the base portion of the rubber member have centrally aligned openings and an internally threaded sleeve 45 lies in the opening in the rubber member and is secured by being vulcanized to the rubber member. The head of bolt 46 provides supporting means for the leg and its shank 47 is screwed into the metal sleeve 45 of the isolator. This isolator device is formed as a unitary structure and can be readily attached to or detached from the bottom of the table leg.

It will be observed that the rubber member portion of the isolator devices supports the leg or the table under compression and is adapted to absorb vibration and shock transmitted from the car floor or wall so that very little shock or vibration reaches the table 10.

The invention may be modified in various respects as will occur to those skilled in the art and the exclusive use of all modifications as come within the scope of the appended claims is contemplated.

What is claimed is:

1. A vibration isolator device for use between a furniture leg and a supporting stud having a threaded shank comprising, a rubber member having a bowl-shaped upper portion and a cylindrical base portion of less diameter with a central aperture therethrough, an internally threaded sleeve in the aperture of the base portion of the rubber member for receiving the stud shank, a flanged metal annular base member fitting over the cylindrical base portion of the rubber member formed with a bottom opening for receiving said sleeve therein, said cylindrical base portion of the rubber member being bonded to the flanged metal annular base member and to said threaded sleeve, and an imperforate metal plate for attachment to the furniture leg entirely overlying the open top of the bowl-shaped upper portion of the rubber member to which the latter is bonded.

2. A vibration isolator device for use between a furniture leg and a supporting stud having a threaded shank comprising, a rubber member having a bowl-shaped upper portion and a reduced diameter cylindrical base portion with a central aperture therethrough, an internally threaded sleeve in the aperture of the base portion of the rubber member for receiving the stud shank, a metal annular base member provided with an upstanding flange fitting around the reduced diameter base portion of the rubber mem-

ber and formed with a bottom opening into which said sleeve is extended, said reduced diameter base portion of the rubber member being bonded to the flanged metal annular base member and to said threaded sleeve, and an imperforate metal plate to which the bowl-shaped upper portion of the rubber member is bonded, said plate entirely overlying the open top of the bowl-shaped upper portion of said rubber member and extending therebeyond adapted for securement to the end of the furniture leg.

3. In a vibration absorbing mounting, a rubber member having a bowl-shaped upper portion and a reduced diameter cylindrical base portion with a central aperture therethrough, an internally threaded sleeve extending through the aperture in the base portion, a flanged metal annular member surrounding the cylindrical base portion of the rubber member formed with a bottom opening into which said sleeve is received, said base portion of the rubber member being bonded to the flanged metal annular member and to the sleeve, and an imperforate attachment plate overlying the open top of the bowl-shaped upper portion of the rubber member to which the latter is bonded.

4. A vibration absorbing mounting for application between an object to be supported and a support member comprising, an imperforate attachment plate secured to said object, a rubber member having a bowl-shaped upper portion bonded to said attachment plate and a reduced diameter cylindrical base portion with a central aperture therethrough, said attachment plate extending entirely across the open top of the bowl-shaped portion of said rubber member, an internally threaded sleeve extending through the aperture in the base portion of the rubber member, a flanged metal annular member surrounding said cylindrical base portion formed with an opening in its bottom through which said sleeve extends, said base portion of the rubber member being bonded to the annular member and to said sleeve, and means engaging the internally threaded sleeve for securing the rubber member to the support member.
